UNITED STATES PATENT OFFICE.

EMORY STOCKWELL, OF STAMFORD, CONNECTICUT, ASSIGNOR TO THE YALE & TOWNE MANUFACTURING COMPANY, OF SAME PLACE.

PERMUTATION-LOCK.

SPECIFICATION forming part of Letters Patent No. 291,701, dated March 4, 1884.

Application filed December 1, 1882. (Model.)

To all whom it may concern:

Be it known that I, EMORY STOCKWELL, of Stamford, in the county of Fairfield and State of Connecticut, have invented certain new and 5 useful Improvements in Dial-Locks, of which the following is a specification.

My invention relates to improvements for insuring the proper action of the fence of a combination-lock under all circumstances, so 10 that the lock can never fail to operate in consequence of the fence sticking; also for rendering the lock exceedingly difficult to pick, if not absolutely unpickable.

Heretofore many dial-locks have failed to 15 operate, even when the other parts were in good working order, from the fact that the fence failed to drop into the notch in the operating-cam at the proper time, so as to cause the retraction or unlocking of the bolt. This 20 failure has been due in many cases to the sticking of the fence upon its arbor either by rust or jamming of some sort. When this occurred, the fence would not fall into the notch of the operating-cam. Hitherto there has been 25 no way, except by the force of gravity or a spring, to overcome the sticking of the fence, and these have both been found to be unreliable for the purpose. I prevent sticking of the fence by a construction which is positive and 30 certain in its action, which does not depend on either a spring or gravity, and which cannot fail without an absolute breaking of the parts.

In the accompanying drawings, illustrating 35 my improvements, Figure 1 is a central horizontal section of a dial-lock substantially such as shown in my United States Patent No. 261,271, granted July 18, 1882. Fig. 2 is a vertical section of the same on the line 22 of Fig. 40 1. Fig. 3 is a horizontal section on line 33 of Fig. 2; and Figs. 4 and 5 are views similar to Figs. 2 and 3, showing a formal modification of my improvements.

I will only describe in detail, by the use of 45 reference-letters, such parts as constitute my improvements and as are immediately related to them in position and function.

A indicates a balanced fence, of which B is the fixed arbor, and C a rotary sleeve surrounding the arbor and forming the immediate pivotal bearing of the fence.

D indicates the lock-bolt having a suitable recess, E, for one arm of the fence, and F the operating-cam provided with a suitable notch, G, for the other arm of the fence.

55

H in Figs. 1, 2, and 3 indicates a pointed toothed wheel, which is attached to or may be a part of the sleeve C.

I indicates a pin or lug on the operating-cam adapted to enter the notches and engage 60 with the pointed teeth of the wheel H and rotate the wheel and sleeve a short distance intermittently whenever the cam is turned one revolution in either direction. In Figs. 4 and 5, instead of this pointed toothed wheel and 65 lug, is shown an ordinary spur-wheel, K, connected with the sleeve and gearing with another spur-wheel, L, secured to the operating-cam or cam-spindle or dial-arbor. When this latter means of rotating the sleeve is employed, 70 the result will be a constant rotation of the sleeve whenever the cam is rotated, instead of a slight intermittent rotation. It is preferable to provide a rim, M, on the sleeve to separate the end of the fence-journal from the 75 screw-cap of the arbor B, so that the rotary bearing-surface of the fence will be on the rotary sleeve at every point; but a rotary sleeve between the fence and its arbor without such a rim is within the scope of my invention.

80

It will be obvious that the mere insertion of a sleeve between the fence and its arbor, without the provision of any special means within the lock for turning the sleeve upon the arbor, will diminish the chances of the operation of 85 the fence becoming obstructed or prevented by sticking at least fifty per cent., because, should the fence stick to the sleeve, the sleeve may not stick to the arbor, and vice versa. The sleeve therefore reduces the liability to 90 sticking very materially of itself, and is, even when applied alone, a useful improvement; but when it is provided with some means—for example, such as the two means above described in detail—suitable for the purpose all 95 permanent sticking is rendered impossible.

From the foregoing it is evident that when the sleeve is moved the friction between the fence and the sleeve will tend to cause the fence to fall toward one side or the other. Should 100 any sticking occur between the fence and sleeve, the force exerted to cause the fence to

move will only be the greater. Now, suppose that the tumblers of the lock are properly set and the arbor is moved so as to bring the notch of the cam underneath the fence, the continued 5 revolution of the dial will positively force the fence into the cam-notch, so that the lock can be unlocked, and under no circumstances can this fail through the sticking together of any parts.

10 Heretofore, as above stated, it has been necessary, either by means of a spring or gravity, to cause a tendency of the fence-lever to always rest against the periphery of the cam or tumblers, or both. Hence, in every revolution 15 of the cam, when its notch comes underneath the fence, the latter, unless it sticks so as not to work at all, bears hard upon the tumblers. This is a great aid to picking and very much weakens the security of the lock.

20 With my construction, when the dial is revolved in one direction, the corresponding revolution of the sleeve causes the balanced fence to gently tip away from the cam and tumblers altogether, while when revolved in 25 the other direction the contact is so light, owing to the nice balance of the fence and the absence of any spring or weight to thrust it against the cam, as to be inappreciable. Hence with this construction picking is rendered very 30 difficult, if not impossible, because the picker cannot tell by sound or feeling whether the fence enters a tumbler-notch or not, and so cannot pick up the tumblers in the usual way. My invention, however, comprehends the use

of a loose sleeve between a lock-fence and its 35 arbor, even if the fence be not a balanced fence. In case it be a balanced fence, there will necessarily have to be some special means provided for throwing the fence; but if it be not a balanced fence, but a fence thrown by gravity or a spring in the ordinary way, then the sleeve is a very useful improvement to prevent sticking; but I prefer to use a balanced fence, for the reasons already stated.

Although I have illustrated my improvements in connection with a well-known type 45 of dial-locks, they are also applicable to other classes of locks, and some may be used without others, as will readily be perceived by those skilled in the manufacture of locks.

I am aware that it is not new to employ a

rotary bearing for a fence of a lock, and I do

not claim that, broadly.

Having thus described my invention, what I claim as new, and desire to secure by Letters 55 Patent of the United States, is—

In a lock, the combination of a balanced fence, its arbor, a moving bearing between them, and means for moving the bearing on the arbor, substantially as set forth.

In testimony whereof I have hereunto subscribed my name this 22d day of November, 60 A. D. 1882.

EMORY STOCKWELL.
